UNITED STATES PATENT OFFICE

128,148

DESIGN FOR A BROOCH OR SIMILAR ARTICLE

Angela Steinreich, Los Angeles, Calif.

Application August 14, 1940, Serial No. 94,420

Term of patent 3½ years

To all whom it may concern:

Be it known that I, Angela Steinreich, a citizen of the United States of America, residing in the city of Los Angeles, county of Los Angeles, and State of California, have invented a new, original, and ornamental Design for a Brooch or Similar Article, of which the following is a specification, reference being had to the accompanying drawing, forming part thereof;

Fig. 1 is a front elevational view of a brooch or similar article, showing my new design; and
Fig. 2 is a side elevational view thereof.
The bars are lined to show contrasting colors.
I claim:
The ornamental design for a brooch or similar article, substantially as shown and described.

ANGELA STEINREICH.
